UNITED STATES PATENT OFFICE.

TRUMAN W. POST, OF NEW YORK, N. Y., ASSIGNOR TO ARMS PRODUCTS COMPANY, OF NEW YORK, N. Y., A CORPORATION OF NEW YORK.

ADAPTER FOR HAND-GRENADES.

1,311,006.

Specification of Letters Patent. Patented July 22, 1919.

Application filed March 7, 1918. Serial No. 220,984.

To all whom it may concern:

Be it known that I, TRUMAN W. Post, a citizen of the United States of America, residing in the city, county, and State of New York, have invented certain new and useful Improvements in Adapters for Hand-Grenades, of which the following is a specification.

My invention relates to an adapter for hand grenades of the shrapnel type, gas bombs, smoke bombs, star shells, etc., and in fact to any of the small grenades or bombs now commonly thrown by hand and provided with hand controlled mechanism for igniting a time fuse, the present invention providing means by which such projectiles may be easily and quickly adapted for firing from a gun. For simplicity of illustration and description, I have indicated herein the application of the invention to a hand grenade of the shrapnel type; but it is to be clearly understood that the same means may be applied to other projectiles of similar type, of which there are many that come within the scope of my invention.

The object of my invention is to provide means whereby grenades or other projectiles of the hand thrown type may be practically instantaneously adapted for firing from a gun and with equal facility be readapted for hand throwing by simply pulling the adapter from the projectile. By adapting the grenade for gun firing, I make it possible to project the ordinary hand thrown device a much greater distance than it can possibly be thrown by hand, and my adapter is of such construction that it adapts the grenade for gun firing, while the safety devices provided to prevent its accidental or premature explosion are still in operation. Moreover, the construction is such that the adapter may be separated from the grenade in the simplest and most expeditious manner, so that the grenade may be again thrown by hand as usual.

In the accompanying drawings,

Figure 1 is a broken side elevation of a U. S. grenade, showing in longitudinal section an adapter applied thereto in which my invention is embodied in one form;

Fig. 2 is a perspective of the adapter shown in Fig. 1;

Fig. 3 is a section through a modified construction;

Fig. 4 is a perspective of the usual safety cap of a grenade of U. S. type;

Fig. 5 is a perspective of another construction of the adapter shown in Fig. 2;

Fig. 6 is a broken side elevation of a 60 Mills grenade, showing my adapter applied thereto;

Fig. 7 is a broken elevation at right angles to Fig. 5;

Fig. 8 is a perspective of the adapter of this type of grenade; and

Fig. 9 is a plan view thereof.

Referring to the drawings, I have shown in Fig. 1 a grenade employed by the U. S. Army, comprising a shell or casing 10, provided at one end with a head piece 11 which carries the fuse and detonator tube 12, while at its opposite end is a fill hole normally closed by a screw plug 13. The primer cap 14, carried by the head, is struck by the hammer 15 pivoted at 16 and subject to the action of the hammer spring 17 coiled on the pivot pin 16. The hammer is normally held in cocked position by the lever 18 pivoted at 19 on a bracket 20, but released by swinging the lever 18 to one side as the grenade is thrown. In order to protect the primer 14 from an accidental blow, a sheet metal hood 21 is provided which fits over the head piece 11 and has at one end a hook flange 22 engaging the lip 23 at one side of the head, while its sides are perforated in register with the holes 24 in the wings 25 on the head 11 to receive the retaining cotter pin 26 which lies in the path of the hammer 15. Ordinarily in preparing the grenade for use, the cotter pin 26 is withdrawn, the cap 21 removed, leaving the hammer 15 free to rotate as soon as the lever 18 is swung out of obstructing position.

In order to adapt this grenade for firing in a gun, I have provided a grenade carrier in the form of a disk 27 of slightly greater diameter than the grenade, but substantially corresponding to that of the bore of the gun, diagrammatically illustrated by the dotted lines 28. On one face of the disk 27 I provide, in any suitable way, as by casting, forming, riveting, welding, or otherwise, members for engaging the head of the grenade. These members here comprise a nose piece 29 adapted to engage the lip 23 of the head 11 (see Fig. 1), and side flanges 30 and 31 to embrace the opposite sides of the head 110

11 with a friction fit. I may also provide another flange 32 which rests upon the edges of the wings 25. On the opposite face of the disk I provide a cartridge support or tube 33, perforated at 34 to permit the escape of the gases on the explosion of the cartridge 35. At the discharge end of the cartridge above the packing wad 36 I provide a substantially rigid plate or wad 37, adapted to 10 impinge against the firing pin 38. This firing pin may be formed in any suitable way. I have here shown it as an angled strap struck from a plate of sheet metal, secured at the lower face of the disk 27 with the pin 15 end of the arm projecting through a hole 39 in the disk which registers with the primer 14 in the head of the grenade. The cartridge carrier 33 is of such diameter that it fits within the conical breech chamber 40 of the 20 gun and presents the primer 41 of the cartridge to the firing pin 42 of the gun.

The operation of the adapter is readily understood. The safety cap 21 of the hand grenade having been removed (and the cotter pin 26 reinserted, or not, through the 25 holes 24), the nose 29 of the adapter is caught beneath the lip 23 at the head of the grenade, and the adapter is pressed down on the head until the latter is firmly seated 30 against the disk 27 and the head 11 firmly gripped by the friction wings 30 and 31 and rests against the stop 32. A cartridge 35 having been inserted in the carrier 33, the 35 grenade is now dropped down the bore of the gun 28 and comes to rest in the breech thereof in position for firing. When the gun trigger (not shown) is pulled, the firing pin 42 is driven against the primer 41 and the explosive charge of the cartridge ignited, 40 forcing the walls of the shell through the perforations 24 in the carrier 33. This not only permits the gases to escape into the breech chamber, but also rivets the cartridge shell to the carrier, so that the cartridge is 45 ejected with the grenade and the carrier 33 from the gun. At the moment of the explosion of the cartridge charge, the wad 36 and facing plate 37 are blown against the firing pin 38, driving the latter against the primer 14, the firing of which ignites the 50 fuse of the grenade. The pressure of the gases from the cartridge charge against the disk 27 of the adapter drives the latter out of the gun with the grenade. During the 55 flight of the grenade, the adapter may or may not become separated therefrom.

In Figs. 2 and 3 I have shown a modified arrangement of the firing pin for the adapter, and have also shown the safety cap 21 of 60 the grenade in position on the grenade head engaged by the adapter. While the firing pin of Figs. 1 and 2 will also broach this cap 21 and strike the primer 14 of the grenade, I prefer the construction shown in disk 57 with pin 58, which, in the inserted

Fig. 3 when the cap 21 is retained on the 65 grenade. As here shown, the firing pin 43 of the adapter is now carried by a metal disk 44 overlying the wad 36 of the cartridge and passing through the hole 39 in the disk 27. When the cartridge is fired, the pin 43 70 penetrates the sheet metal cap 21 and strikes the primer 14, thus igniting the grenade fuse just as in the construction first described. The retention of the cap 21 renders the use of the adapter still more safe, 75 and the grenade can drop out of the gun without danger of igniting the fuse even should the lever 18 be struck.

In Fig. 5 I have shown the grenade gripping elements of the adapter struck from a 80 plate of sheet metal spot welded to the disk 27.

In Figs. 6, 7, 8, and 9 I have shown the adapter modified to operate the well known Mills grenade in common use in the British 85 armies. In this grenade, the head of the firing pin 45 is normally engaged and held against the action of its firing spring by flanges 46 formed on the end of the safety 90 lever 47. The latter is struck from sheet 95 metal and is provided with a trunnion pin 48 which has bearings in wing pieces 49 formed at the head of the grenade. A cotter pin 50 passing through these wing pieces, holds the lever 47 in safety position. In 100 this position, the head of the firing pin is slightly drawn out of the shell of the grenade, exposing its stem. The adapter in the form here shown comprises, as before, the disk 27, upon the grenade face of which I 105 form or secure in any suitable way a device adapted to engage the head of this Mills grenade. As here shown, the engaging means comprises a pair of legs 51 and 52 freely straddling the head of the firing pin 110 so as not to interfere with the latter, but engaging beneath the trunnion pin 48 with a wedge action, thus holding the adapter firmly to the head of the grenade. If desired, a tongue 53 may be formed between 115 the legs 51-52, which, in the adjusted position of the adapter, engages beneath the head of the firing pin 45 and thus adds to the security of the lever 47 in holding the firing pin against premature release. The 120 legs 51 and 52 are here shown integral with base straps 54-55 secured to the disk 27 by welding, soldering, riveting, or otherwise, and upset at their free ends 56 to fit against the shoulders of the wing pieces 49 on the 125 grenade, thus forming stops which position the adapter with the perforation 39 of the disk in alinement with the head of the firing pin 45 of the grenade. The opposite face of the adapter is provided with a shell holder 33 like that first described, and the shell carries at its discharge end, a metal disk 57 with pin 58, which, in the inserted

position of the shell, passes through the perforation 39 in the adapter disk 27.

To adjust the adapter on the grenade, it is merely necessary to shove the legs 51-52 beneath the trunnion pin 48 until the stops 56 halt the disk 27 with its hole 39 in register with the firing pin 45 of the grenade. When the cartridge 35 is fired, the pin 58 on the disk 57 is driven against the firing 10 pin 45 of the grenade with such force that the retaining flanges 46 of the safety lever, and the tongue 53 (if used) of the adapter, are either broken off or deformed sufficiently to release the firing pin 45. The latter, thus 15 released, is driven by its spring against the primer of the grenade and ignites its fuse in the usual manner.

I have thus illustrated several constructions in which my invention may be embodied. Various other arrangements will readily occur to those dealing with the problem by which the same result may be obtained. The underlying thought of my invention is to provide an adapter which may 20 be applied to a hand grenade without altering its construction or releasing its safety mechanism, and by the use of which the grenade may be fired from a grenade gun. Furthermore, the ignition of the grenade is 25 dependent upon the explosion of the charge of the gun cartridge which sets in motion some device directly or indirectly firing the grenade primer. The invention may be applied to other types of grenades, bombs, 30 shells, etc., without departing from what I claim as my invention, and in the following claims I use the term grenade in a sense broad enough to cover such devices. Similarly, I refer to "means associated with the 35 grenade carrier or attachment" for firing the grenade, in a sense broad enough to cover the firing pin mounted either on the carrier or on the cartridge or otherwise.

I claim:

40 1. A device for adapting a fused grenade for gun firing, comprising a grenade carrier substantially corresponding in diameter to the gun bore, means on said carrier for engaging the grenade, a cartridge support on said carrier, and means operated by the explosion of the cartridge for causing the ignition of the grenade fuse.

45 2. A device for adapting a fused grenade for gun firing, comprising a grenade carrier disk substantially corresponding in diameter to the gun bore, means on one side of said disk for engaging the grenade, a cartridge support on the opposite face of said disk, and means operated by the explosion of the cartridge for causing the ignition of the grenade fuse.

50 3. A device for adapting a fused grenade for gun firing, comprising a grenade carrier substantially corresponding in diameter to

the gun bore, means on said carrier for engaging the grenade, a cartridge support on said carrier, said carrier being perforated to permit the passage of a firing pin therethrough.

4. A device for adapting a fused grenade 55 for gun firing, comprising a grenade carrier, means on said carrier for engaging the grenade, a cartridge support on said carrier, said carrier being perforated to permit the passage of a firing pin therethrough, in combination with a cartridge having at its discharge end a firing pin adapted to pass through said perforation in the carrier.

5. The combination with a fused grenade 60 having a firing head, of a device for adapting the grenade to gun firing, comprising a carrier substantially corresponding in diameter to the gun bore, and means on said carrier for engaging the grenade head to hold said parts in assembled relationship 65 during firing.

6. The combination with a fused grenade 70 having a firing head, of a device for adapting the grenade to gun firing, comprising a carrier, and means on said carrier for engaging the grenade head to hold said parts 75 in assembled relationship during firing, together with means on said carrier for supporting a cartridge.

7. The combination with a fused grenade 80 having a firing head, of a device for adapting it for gun firing, comprising a carrier having means for securing it to the firing head of the grenade, said carrier being perforated to permit the passage of a firing pin 85 therethrough to cause the ignition of the grenade fuse on the explosion of the gun charge.

8. The combination with a fused grenade 90 having a safety device for preventing premature ignition of its fuse, of a device for adapting said grenade to gun firing, said device comprising a carrier having means 95 for securing the same to the grenade, together with means operative upon the explosion of the gun charge for causing the ignition of the grenade fuse irrespective of the condition of the safety device on the grenade.

9. The combination with a fused grenade 100 having a primer, of a gun firing attachment therefor adapted to enter the gun breech in firing position, together with means operated by the explosion of the gun charge for causing the ignition of the grenade primer.

10. The combination with a fused grenade 105 having a primer, of a gun firing attachment therefor adapted to enter the gun breech in firing position and to carry the gun charge, together with means operated by the explosion of the gun charge for causing the ignition of the grenade primer.

11. The combination with a hand grenade

of a gun firing attachment comprising a member of greater diameter than the grenade and substantially corresponding to the bore of the gun, and means for securing the same to the grenade.

12. The combination with a hand grenade of a gun firing attachment comprising a member of greater diameter than the grenade and substantially corresponding to the bore of the gun, and means for securing the same to the grenade, together with a cartridge carrier on said member adapted to receive the gun cartridge and present the primer thereof to the firing device of the gun.

13. The combination with a hand grenade having a primer and means for firing the same, of a gun firing attachment for the grenade and associated means for firing the grenade primer.

14. The combination with a hand grenade having a primer, firing means therefor, and

safety means for preventing premature firing of the primer, of a gun firing attachment for the grenade and associated means for firing the grenade primer while said safety means are in operative position.

15. The combination with a hand grenade having firing means and associated safety means for preventing premature operation of said firing means, of a gun firing attachment and associated means for firing the grenade while said safety means are in operative position.

16. The combination with a hand grenade having firing means, associated safety means for preventing premature operation of the firing means, and means for locking said safety means in position, of gun operated means for firing the grenade while said locking means is in operative position.

In testimony whereof I have signed my name to this specification.

TRUMAN W. POST.
